(57) **CLAIM**

The ornamental design for an electronic camera, as shown and described.

DESCRIPTION

FIG. 1 is a top, front and side perspective view of an electronic camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2; and,

FIG. 7 is a side elevational view thereof from the right of FIG. 2.

The portions of the electronic camera in broken lines are shown for illustrative purposes only and form no part of the claimed design.
